SEAMLESS MOLDED FABRIC BREAST RECEIVING AND SUPPORTING MEMBERS AND MEANS FOR MOLDING THEM

Richard MacHenry, Chester, Pa., assignor to American Viscose Corporation, Wilmington, Del., a corporation of Delaware

Application December 5, 1947, Serial No. 789,868

7 Claims. (Cl. 2—42)

1

This invention relates to seamless molded fabric breast receiving and supporting members, and to means for molding the members from a flat fabric.

Cups or pockets for brassieres and similar garments are intended to fit snugly about the breast and to hold it in properly uplifted position to impart the desired esthetic shape. Molded seamless cups or pockets which have been available heretofore have had the disadvantage that the bottom sags in use, with inevitable drooping of the breasts. This sagging of the bottom of the prior art seamless cups under the weight of the breast is an inherent defect in the cups and the inescapable result of the shape imparted to the fabric during the molding or shaping operation. The practice has been to shape the fabric on a mold having a generally round peripheral surface of the same curvature throughout. Regardless of size, those cups always comprise an amount of fabric in excess of that required for snug conformance of the cup to the contours of the breast which they are intended to fit, and for supporting the breast in the desired position. When the cups are worn, the excess fabric constitutes slack in the cup which permits the major portion of the load, i. e., the weight of the breast, to be concentrated directly at the bottom of the cup. Due to the fact that the curvature of the surface of the cup is the same at all portions, the bottom "gives" and sags out of the desired shape under the load. The sagging can only be counteracted by very tight adjustment of the straps or the like of the garment comprising the cups, which causes a drag or pull on the shoulders and around the torso of the wearer. Drag or pull is exerted in any case, because the strain placed on the straps, and therefore on the body of the wearer, by sagging of the bottom and drooping of the breasts, is of at least the same magnitude as the strain caused by tightly drawn straps. So long as the peripheral surface of the cups is kept in the desired seamless or tuckless condition, the tendency of the bottom to sag in use cannot be overcome without strain on the body of the wearer.

The object of this invention is to provide new seamless molded fabric breast receiving and supporting members which comprise only sufficient fabric to insure snug fit of the member about the breast and to support it in properly uplifted disposition. Another object is to provide such seamless members the bottom of which functions to distribute a greater portion of the weight of the breast toward and along the sides of the member than has been the case with prior art

2

seamless members. Another object is to provide seamless members the peripheral surface of which is of such shape that the breast is held in the esthetically desirable uplifted position without strain on the body of the wearer or interference with complete freedom of body movement. A further object is to provide a novel mold of special shape for use in molding the new members from a flat fabric.

The seamless breast receiving and supporting members of the invention are molded or shaped on a mold having a peripheral surface, the outline of which is based upon a concept which is wholly novel in the manufacture of members of this type. The mold is generally breast-shaped, but one portion of the peripheral surface comprises a generally trapezoidal portion extending from a point adjacent the base of the mold toward a plane adjacent the apex, but preferably extending clear to the apex and has a reduced curvature (or convexity as viewed externally) as compared to the curvature of the remaining portion of the surface. When the trapezoidal portion extends from the base to the apex, it comprises a spherical triangular area, any portion of which other than that adjacent the apex may be regarded as the trapezoidal portion referred to hereinabove. The portion comprising the generally trapezoidal portion is preferably flat or almost flat between the sides joining it to the remaining portion of the surface. When a fabric is molded or shaped on the novel mold of the invention, the surface of the resulting breast-receiving and supporting member has imparted to it a corresponding portion adapted to fit beneath the breast and which comprises a generally trapezoidal portion having a reduced curvature as compared to the curvature of the remaining portion of the surface of the member. Due to the reduced curvature of the flat or almost flat portion molded integrally with or "built into" the member, the member comprises a reduced fabric surface as compared to the fabric surface which would be present if the surface of the member had the same curvature throughout. Because of the difference in curvature of the several portions of the surface of the member and the consequent reduction in the amount of fabric comprising the member on the supporting side, the member comprises only sufficient fabric to insure snug fit of the member to the contours of the breast, when the member is of any given size correlated to the size of the wearer. The curvature of the generally trapezoidal portion is such that the bottom of the member is "self-

loading," i. e., under load it "rounds out" to the shape of a shallow catenary curve corresponding to the proper breast shape desired. Since the member is free of slack, and the bottom cannot sag, the bottom accepts a portion of the load but also functions to distribute a greater proportion of the weight of the breast toward the opposite ends of the catenary and along the sides of the member than would be done by a member formed without the portion of reduced curvature. The breast is suspended in the catenary, from the opposite ends thereof, in such a manner that the weight is more equally distributed and the breast is held in proper uplifted condition. The portion of reduced curvature performs the function of distributing the weight of the breast in the member, in such a fashion that the breast itself serves to mold the member to the final desired shape. The member is thus "rounded out" to shape, and the breast is molded to and supported in uplifted position by virtue of the cooperation of the breast receiving and supporting member with the breast, and without benefit of any extraneous aids.

The portion of reduced curvature preferably occurs at the center of the bottom of the member, and may occupy up to one-half of the underside of the member. Preferably, the portion occupies approximately one-third of the underside of the member.

The new breast receiving and supporting members comprising the self-loading bottom are made by molding a flat fabric comprising thermoplastic yarns on a generally breast-shaped mold, a portion of the peripheral surface of which comprises a generally trapezoidal portion as described herein. In the preferred embodiment of the invention, the flat fabric comprises thermoplastic, potentially heat-shrinkable yarns in the non-thermoplastic, non-softened condition, and the fabric, after fitting thereof to the contours of the mold, is uniformly heated to effect shrinkage of the individual heat-shrinkable yarns, thereby producing, by such shrinkage, a bust receiving and supporting member having molded directly therein a segment comprising the generally trapezoidal portion, and stabilized in the shape of the mold. By "fitting" the fabric to the contours of the mold is meant placing the fabric on the mold and smoothing it or pulling it out to conform to the mold and so that it is substantially free of wrinkles or folds, without subjecting it to a tension substantially greater than the tension to which a knitted fabric is subjected when it is pulled out to its normal, full machine dimensions.

The fabric may be woven or knitted, and is preferably knitted, but in any case, when the fabric comprises heat-shrinkable yarns, as is preferred, the individual yarns in the shaped fabric are substantially uniformly shrunk and reduced in diameter, after the heat-treatment, as compared to the diameter of the yarns in the flat fabric, and prior to the heating and shrinking step. Knitted fabrics of all types may be molded in accordance with the invention. As an example, the fabric may be of the circular knit type, the stitches of which are formed by interlocking loops. In the normal condition of such a fabric, when the fabric is pulled out to its normal machine dimensions, each of the loops making up the stitches is comprised of two straight sides and a round, relatively slack, end. As a result of shrinkage and compaction of the yarn comprising each of the loops, which is effected when the

fabric is fitted to the single mold member of the invention and heated, the slack is removed from the round end of each of the loops, with straightening or tautening thereof. In the shaped and stabilized fabric, i. e., in the molded bust receiving and supporting members, each of the loops, comprises two straight sides and a straight end, joined by substantially straight or squared corners. Shrinkage of the individual yarns and straightening of the normally slack ends of the loops serves to stabilize the fabric in the shape of the mold.

Again, the fabric may be of the warp knit type, that is, a multiple warp fabric in which the warps form an interlocking system. In fabrics of that type, each wale, in each course, is joined to a wale in another course, by yarns extending diagonally of the wales. In their normal state, the yarns forming the loops comprising the wales or ribs of the fabric are comparatively soft and full, and the loops are comparatively loose and slack. The yarn extending diagonally of the wales is also comparatively full and slack and, upon close examination, the diagonally extending yarns appear to lie in a loose, bulky condition on the back of the fabric, the individual fibers of the yarn being spread out and discernible. When, such a warp knit fabric comprising heat-shrinkable potentially thermoplastic yarns is fitted to a single mold member having a portion comprising a generally trapezoidal portion, in accordance with the invention, and heated, the yarns forming the ribs or wales, and the diagonally extending yarns which join the courses together, are individually shrunk and compacted, and reduced in diameter. The loops forming the wales or ribs in the shaped and stabilized fabric appear to be elongated, with their opposite sides drawn more closely together than in the flat fabric, while the yarns extending diagonally of the wales are drawn taut and lie flat on the back of the fabric.

Regardless of the type of knitted fabric molded, when it comprises heat-shrinkable yarns, it is stabilized in the shape of the mold by removal of the slack resulting from shrinkage of the yarns uniformly at all portions of the fabric, and the molded fabric member is substantially lacking in stretchability. The stitches of the shaped knitted fabrics comprising the individually shrunk yarns may slip relatively to each other, as for instance, when they are handled during laundering, but do not "give" under stress. The support provided by the portion comprising the generally trapezoidal portion of reduced curvature molded into the members is reinforced by the slack-free condition of the individual stitches of the fabric.

The invention is illustrated in the accompanying drawing in which:

Figure 1 is a plan view of a mold according to the invention;

Figure 2 is a side view of the mold of Figure 1;

Figure 3 is a fragmentary view, in section, showing details of the mold of Figures 1 and 2;

Figure 4 is a plan view of the bust receiving and supporting member of the invention;

Figure 5 is a side view of the member of Figure 4;

Figure 6 is an elevation of apparatus comprising the mold of Figures 1 and 2; and

Figure 7 is a view of an assembled brassière comprising the novel breast receiving and supporting members of the invention.

Referring to Figures 1 and 2, there is shown a mold 2 of generally breast shape, the peripheral

surface 3 of which comprises a portion 4 comprising a generally trapezoidal portion extending from the upper edge of the shallow groove 5 by being adjacent the base of the mold, to the apex. As actually shown, portion 4 comprises a spherical triangular area defined by curved sides 16 and 17. The groove 5 is provided so that when the fabric is heated in situ on the mold, the yarns in the portion thereof overlying the groove are spaced away from the surface of the mold and are not affected by the heat or are affected to a lesser extent than the remaining yarns, and either do not shrink or shrink to a lesser extent, to provide a comparatively soft sewing edge on the breast receiving and supporting member. Instead of a groove, the mold may be provided with an insert or band of a material which does not conduct heat, the portion of the fabric in contact with such insert being substantially unaffected by the heat treatment. Imbedded in the base of the mold, and extending peripherally thereof is a heating wire 6 having connections to a source of electric current (see Fig. 3). The wire is imbedded in a non-conductive cementing material 15. After the fabric has been molded to the shape of the mold, the wire is energized and heated, the heat serving to activate the thermoplastic yarns in the portion of the fabric overlying the wire to a softened or melted condition, whereby the molded fabric member is readily separated from the remaining portion of the fabric. Groove 5 may be, and as shown, is, irregular in outline, and is wider at one side of the mold than at the other to provide a soft edge 7 (Fig. 4) of varying depth on the molded fabric member. That portion of the soft edge having the greater width occurs at the top of the member in use and permits the edge to be doubled upon itself during sewing and finishing.

Figures 4 and 5 are illustrative of a bust receiving and supporting member obtained by shaping a flat knitted fabric comprising thermoplastic yarns on the mold of Figures 1 and 2. The shaped fabric has a peripheral surface 8 having a curvature corresponding to the peripheral surface of the mold and comprising a portion 9, comprising a generally trapezoidal portion of reduced curvature and corresponding in outline to portion 4 of the mold. As shown, segment 9 is almost flat between the sides of the trapezoid joining it to the remaining portion of the member.

Figure 7 illustrates a brassiere comprising breast receiving and supporting members in accordance with the invention, the straps 18 and 19 being secured at the outwardly jutting points 20 of the member, and to the body encircling member 21.

The fabric fitted to the contours of the mold may be heated to effect uniform shrinkage and reduction in the diameter of the individual yarns of the fabric in any suitable manner. One means for accomplishing this is illustrated in Figure 6. In Figure 6 there is shown a chamber 12 containing a supporting surface 10 which supports a plurality of molds 11 of the type shown more fully in Figures 1 and 2. Steam is injected into the chamber through a pipe 13 and introduced into the interior of the molds through the manifold 13a provided with outlets leading to the interior of the respective molds. Each of the molds 11 is provided with a slip fit ring 14. The fabric comprising the thermoplastic yarns, for example a fabric knitted from heat-shrinkable yarns of a copolymer of vinyl chloride and vinyl acetate, is fitted to the mold, and ring 14 is slipped over the

surface 10 of the mold to hold it in general conformity to the shape of the mold. The steam acting on the fabric causes the yarns to shrink, the fabric being tautened to the shape of the mold by such shrinkage. The fabric shaped on the mold is cooled, preferably while it is in place on the mold, to set the yarns in the shrunk state, for instance, by subjecting it to a stream of cold air. Instead of heating the fabric on the mold in the manner described, other means for applying a controlled amount of heat, either wet or dry, uniformly to all portions of the fabric may be used. For example, the molds may be heated internally, by means of hot water, heating coils, etc., the heat being transmitted to the fabric through the mold. The mold may be formed of any suitable material, and is usually formed of heat-conductive metal. Preferably, the temperature to which the fabric is exposed, and the duration of the heat treatment are controlled so that the yarns or filaments shrink spontaneously without undue softening or coalescence, the conditions of the heat treatment depending upon the particular heat-shrinkable yarns or filaments comprising the fabric.

While it is preferred to stabilize the flat fabric in the shape of the new mold by shrinkage of the individual thermoplastic yarns, because of the desirable properties of the molded fabric members thus obtained, such as uniformity of the yarns at all portions of the fabric, a slick smooth feel, and uniform translucent appearance, and the fact that the transverse dimensions of the shaped fabric are the same as the dimensions of the fabric prior to heating thereof, the fabric in the thermoplastic condition may also be stretched over and in conformity with the mold and then set in the stretched condition, or it may be over-stretched and then shrunk back to the shape of the mold.

The flat fabrics may comprise any filaments or yarns, including yarns comprising discontinuous fibers, formed from a thermoplastic material, including the vinyl resins, nylon, cellulose acetate in the thermoplastic state, and the like. When it is desired to effect the shaping by uniform shrinkage of the thermoplastic yarns, the yarns may be formed from filaments or fibers of a thermoplastic material having the capacity to shrink spontaneously while remaining intact when the fabric is heated to a temperature below the melting and decomposition temperatures for the thermoplastic. In a preferred embodiment of the invention, the heat-shrinkable yarns or filaments are formed from fiber-forming resins resulting from the polymerization of one or more substances containing the vinyl radical. Examples of such materials are the acrylate and alkacrylate resins, polymers of vinyl esters such as vinyl acetate, polymers of vinyl ethers such as vinyl acetals, methacrylate polymers, and copolymers or interpolymers of vinyl halides with other organic polymerizable substances containing the vinyl radical.

In a specifically preferred embodiment, the heat-shrinkable yarns or filaments comprise a copolymer of vinyl chloride with vinyl acetate, containing about 90% vinyl chloride in the copolymer molecule, or a copolymer of vinyl chloride and acrylonitrile containing about 55% vinyl chloride in the copolymer molecule. Such filaments or yarns may be rendered heat-shrinkable by subjecting them to a stretch of from 100% to 1200% or more during their production, or subsequently to their production but prior to their

fabrication, and while in a cold unsoftened state, or in somewhat softened and plastic condition. Generally, the filaments or yarns so stretched have, prior to their fabrication, a residual shrinkage capacity of at least 50% at temperatures below the melting and decomposition temperatures for the resin. As an example, such prestretched yarns comprising a copolymer of vinyl acetate and vinyl chloride have a residual shrinkage capacity of at least 50% at temperatures of from 85 to 95° C.

Breast receiving and supporting members having a self-loading bottom constituted by a portion of the peripheral surface comprising a portion of reduced curvature as described herein may also be molded from woven fabrics comprising thermoplastic yarns.

By the practice of this invention, a self-loading, non-sagging bottom is molded integrally with remaining portions of the members, the self-loading bottom being independent of any darts, tucks, seams, or the like in the molded fabric.

The members of the invention may be laundered and manipulated without permanent loss of shape, the shape being immediately restored by molding of the member to the desired shape, by the breast itself, when the members are worn.

I claim:

1. A seamless molded fabric breast receiving and supporting member molded from a flat fabric 30 knitted from thermoplastic heat-shrinkable yarns which exist in the flat fabric in the unshrunk condition, said molded member being stabilized in generally breast-like shape and comprising an edge of irregular outline, said molded member having a peripheral surface comprising a spherical triangular area defined by curved sides extending from the edge of the member, said spherical triangular area being substantially flat as compared to the remaining portion of the peripheral surface, and constituting a self-loading bottom for the member in use, the base of the spherical triangle lying adjacent the edge of the member, the yarns in the molded fabric member other than the yarns comprising the edge being shrunk and substantially reduced in diameter as compared to the yarns in the flat fabric, and the yarns comprising the edge of the member being in substantially the same condition as the yarns in the flat fabric.

2. A seamless molded fabric breast receiving and supporting member stabilized in generally breast-like shape and having a peripheral surface one portion of which comprises an integral, substantially non-stretchable, spherical triangular area defined by curved sides and constituting a self-loading bottom for the member in use, the spherical triangular area being substantially flat as compared to the remaining portion of the peripheral surface of the member and adapted to round-out without sagging to a shallow catenary curve under load in use, the base of the triangle lying adjacent the edge of the member.

3. A seamless molded fabric member as in claim 1, the fabric comprising the member being a circular knit fabric the loops of which comprise two straight sides joined to a straight end by squared corners.

4. A seamless molded member as in claim 1, the fabric comprising said member being a warp 70 knit fabric in which the loops forming the wales

are drawn closely together and the yarns extending diagonally of the wales are drawn taut and lie flat against the back of the fabric.

5. A seamless molded fabric breast receiving and supporting member molded from a flat fabric knitted from thermoplastic heat-shrinkable yarns which exist in the flat fabric in the unshrunk condition, said molded member being stabilized in generally breast-like shape and having a peripheral surface comprising a spherical triangular area defined by curved sides extending from the edge of the member, said spherical triangular area being substantially flat as compared to the remaining portion of the peripheral surface and constituting a self-loading bottom for the member in use, the base of the spherical triangle lying adjacent the edge of the member, the yarns in the molded fabric member other than the yarns comprising the edge thereof being shrunk, and the yarns comprising the edge of the member being in substantially the same condition as the yarns in the flat fabric.

6. A mold of generally breast-like shape comprising an effective molding surface and a non-molding surface, the effective molding surface comprising a spherical triangular area defined by curved sides extending upwardly from the base of the effective molding surface, the base of the spherical triangle lying adjacent the base of the effective molding surface and the spherical triangular area being substantially flat as compared to the remaining portion of the peripheral surface of the breast-like mold, a groove below the effective molding surface and extending peripherally of the mold between the effective molding surface and the non-molding surface, said groove preventing direct contact of the fabric overlying the groove with the heated surface of the mold and having a portion of increased width as compared to the width of the remaining portion thereof, and means arranged below the groove for separating fabric shaped on the mold from unshaped fabric.

7. A mold as in claim 6, said mold being formed 45 of a heat-conductive metal and the means for separating fabric shaped on the mold from unshaped fabric comprising a conductive metal element extending peripherally of the mold, below the groove, and having connections with a source of electric current.
